UNITED STATES PATENT OFFICE.

FRANK W. CHERRY, OF KENILWORTH, ILLINOIS, ASSIGNOR OF ONE-HALF TO FRANK B. WATSON, OF AURORA, ILLINOIS.

SIGNAL.

1,316,082.

Specification of Letters Patent. Patented Sept. 16, 1919.

Application filed January 22, 1918. Serial No. 213,220.

To all whom it may concern:

Be it known that I, FRANK W. CHERRY, a citizen of the United States, and a resident of the village of Kenilworth, in the county 5 of Cook and State of Illinois, have invented certain new and useful Improvements in Signals; and I do hereby declare that the following is a full, clear, and exact description of the same, reference being had to the accompanying drawings, and to the numerals 10 of reference marked thereon, which form a part of this specification.

This invention has reference more particularly to a signal which has means adapted 15 to be illuminated by rays of light from an approaching vehicle to indicate the approach of the vehicle.

An object of the invention is to provide 20 signaling means which will reflect light from an approaching vehicle, and thereby indicate the approach of the vehicle.

Another object of the invention is to provide 25 a signaling means for intersecting roads which will reflect rays of light projected along one roadway and re-direct the rays of light in the direction of the other roadway.

Another object of the invention is to provide 30 a signal adapted to be used at the intersection of a railway and a roadway, and having reflecting means arranged to project rays of light from a vehicle on the railway in a direction down the roadway so as to indicate the approach of a railway vehicle.

It is a further object of my invention to 35 provide a signaling device with a plurality of outwardly facing reflectors arranged to receive light from one direction and to project it in another direction.

Another object of the invention is to provide 40 a signaling device with externally facing reflecting means and a lens co-operating therewith so as to receive light from one direction and transmit it through the lens in another direction.

Another object of the invention is to provide 45 a signaling device with reflectors faced outwardly, and inclosing means for protecting the signaling device which permits entrance of light to the reflecting means and projection of rays of light therefrom.

Another object of my invention is to provide 50 a light reflecting signaling device of

simple construction which can be easily and cheaply made and which is substantially constructed so as to withstand hard usage. 55

My invention also has other objects which will be apparent from the disclosures in the following specification and the accompanying drawings.

The invention (in a preferred form) is 60 illustrated in the drawings and hereinafter more fully described.

On the drawings:

Figure 1 is a plan view of a railroad and 65 intersecting roadway showing my signal applied thereto.

Fig. 2 is a side view of a signal post constructed in accordance with my invention.

Fig. 3 is a similar view looking at the left 70 hand side of Fig. 2.

Fig. 4 is an enlarged horizontal sectional view on the line 4—4 of Fig. 2.

Fig. 5 is a view taken on the line 5—5 of Fig. 4.

Fig. 6 is a view on the line 6—6 of Fig. 4. 75

Fig. 7 is a fragmentary view of a corner of the reflecting structure showing the manner of supporting the reflectors.

Fig. 8 is a fragmentary view on the line 80 8—8 of Fig. 4.

Fig. 9 is a fragmentary view on the line 9—9 of Fig. 4.

Fig. 10 is an enlarged fragmentary horizontal sectional view showing details of construction. 85

As shown on the drawings:

1, indicates a roadway and 2, a railway, which intersects the roadway, 3, an engine or other railway vehicle having a headlight 4, which projects rays of light down the 90 railway at a long distance ahead of the engine or vehicle 3, on which it is mounted so as to light up the track for the engineer or operator of the railway vehicle.

5, indicates as a whole, my signaling device which is arranged at the intersection of the railway 2, and roadway 1, and may be in the form of a post at the side of the railway or roadway, as indicated, or may be suspended, it being necessary only that 100 the signaling device shall be out of the way of vehicles on either roadway and within the path of the rays of light projected by the headlight of the engine, so as to receive

the rays projected from the headlight 4, and reflect them down the roadway at each side of the track to provide a dependable signal that will indicate the approach of 5 the train to the crossing.

The drawing illustrates my signaling device as applied at the intersection of a railroad and a roadway and for the sake of convenience, it will be described hereafter, as so 10 used. However, I wish it to be understood that I contemplate using this signaling device otherwise as it may readily be used at the juncture of two roadways or two railways or in fact, at any place where light 15 may be furnished from a vehicle or other source and reflected by the signaling device to indicate the approach of the vehicle.

This signaling device is preferably constructed at the upper end of a post although 20 it may be provided so as to be suspended from a support. The post construction may be conveniently formed by joining two angle irons 6 with the blocks 7, interposed, and connecting them by the bolts or rivets 8, 25 which are passed through the angle irons and interposed blocks 7. This not only provides a very strong light post, but it is particularly adapted to have other parts of my invention applied thereto. The lower end 30 of this post is set in the ground at the desired point of intersection of the roadway, it being preferable, as shown in Figs. 2 and 3, to set the post in concrete 9, to preserve the post, and make a more substantial footing. 35 This post extends upwardly so that the signaling device on the upper end thereof is in the path of the rays of light from the railway headlight and also so that the reflected rays are clearly visible down the roadway 1. The edges of the flanges of the angle irons adjacent the top of the post are 40 cut out so as to form, or are otherwise provided with the spaced clips 10, and the intermediate clips 11 and 12. A rectangular frame 13, has two opposite sides thereof cut away so as to be entirely open except for the upper and lower strips 14 and 15, respectively, which connect the other two sides of 45 the rectangular frame. These latter sides of the rectangular frame are provided with a circular opening indicated at 16, in Fig. 6, the margin of which is bent outwardly as at 17, in Fig. 4, to receive the tapered edge 50 of the lens 18, which fits in the opening 16, and is held therein by a number of latches 19, secured to the inner face of the rectangular frame and extending over the edge of the lens 18. The clips 10, on the angle irons 6, are bent at right angles to the flange of 55 the angle iron and are connected to the upper and lower strips 14 and 15, respectively, of the rectangular frame, and also to the top and bottom of the sides of the rectangular frame that have the lens. The sides of the 60 rectangular frame are thus at right angles 65

to the flange of the angle irons to which they are connected and the flanges of the angle irons are positioned midway of the width of the sides of the rectangular frame.

Mounted within the rectangular frame and 70 secured to the edges of the angle irons 6, are the reflecting members 20, which are held in place by the clips 11 and 12, the latter of which are bent as shown in Fig. 10, to provide an abutment against which the reflecting member is held and the clips 11, are bent over the edges of the reflecting members so as to clamp the reflecting member against the clips 12, to hold them securely 75 in place. This provides a pair of reflectors 80 at each open side of the rectangular frame having the vertex of the angle formed by the intersection of the reflectors at the center of the opening and the reflectors arranged so that rays of light received through 85 the opening in the rectangular frame will be redirected in two directions by the reflectors 20, through the lenses 18.

For protecting the lenses and reflectors 90 from damage, there is a drum 21, made of coarse screen mesh which incloses the frame of the structure and is supported by lips 22, at the lower corners of the rectangular frame. At the upper corner of the rectangular frame are lugs 23, which are bent inwardly as shown in Fig. 8, and have the 95 conical roof 24, attached thereto by means of the rivets 25. Hooks 26, may be interposed between the conical roof 24 and the lugs 23, so as to engage loops in the upper 100 edge of the drum 21, for holding the drum in place.

The operation is as follows:

The post is set at the intersection of the 105 railway and roadway at the side of the railway and roadway, as shown in Fig. 1, so that the rays of light from the headlight of the engine 3, will be projected against the signaling device. The post is set so that the signaling device has the open side of the 110 frame facing in the direction of the railway so that the reflectors 20, will receive the rays of light from the headlight and redirect these rays of light out through the lens 18, up and down the roadway 1.

With the construction shown in Fig. 4, 115 there are a pair of reflectors at each side of the signaling device so that it is operated by rays of light from a train approaching in either direction and will signal the approach of the train along the roadway at both sides of the railroad track.

For daylight signaling, the posts may be provided with a sign 27, fastened thereon, and facing up and down the roadway 1, to 120 indicate that there is a railway crossing at the point.

There may be instances in which it is unnecessary to have reflectors on both sides of the signaling device, as for instance when 125

the train passes only in one direction and also where it is necessary to project the signal only at one side of the railway track, and I contemplate modifications to meet these conditions.

5 I am also aware that various other details of construction may be varied through a wide range without departing from the principles of this invention, and I therefore 10 do not purpose limiting the patent granted otherwise than necessitated by the prior art.

I claim as my invention:—

1. A signaling device comprising an upright having four radially arranged and substantially equally spaced flanges, reflecting members, means on the outer edges of said flanges at the upper end of the upright for supporting the reflecting members intermediate said outer edges, a rectangular frame surrounding said reflecting members and arranged so that the mid-portions of the frame lie adjacent to said outer edges, lenses in opposite sides of said frame and a circular reticulated inclosure surrounding said frame.

25 2. A signaling device comprising an upright having four radially arranged and substantially equally spaced flanges, reflecting members, means on the outer edges of said flanges at the upper end of the upright 30 for supporting the reflecting members intermediate said outer edges, a rectangular frame surrounding said reflecting members and arranged so that the mid-portions of the frame lie adjacent to said outer edges, lenses 35 in opposite sides of said frame and a circular reticulated inclosure surrounding said frame,

a conical roof surmounting the frame and a sign mounted on the roof.

3. A signaling device comprising a square frame, openings in two opposite sides for receiving light, lenses in the other two sides 40 for transmitting light, and four mirrors rectangularly arranged within the frame adapted to reflect light received through one opening through both lenses.

4. A signaling device comprising a square frame, openings in two opposite sides for receiving light, lenses in the other two sides for transmitting light, and four mirrors 45 rectangularly arranged within the frame adapted to reflect light received through one opening through both lenses, a sloping roof 50 surmounting the frame and a sign mounted on the roof.

5. A signaling device comprising an upright having four radially arranged and substantially equally spaced flanges, reflecting members, means on the outer edges of said flanges at the upper end of the upright 55 for supporting the reflecting members intermediate said outer edges, a rectangular frame surrounding said reflecting members and arranged so that the mid-portions of the frame lie adjacent to said outer edges and 60 lenses in opposite sides of said frame.

In testimony whereof I have hereunto subscribed my name in the presence of two subscribing witnesses.

FRANK W. CHERRY.
